DESIGN FOR A FISH LURE

Myron C. Miller, Seattle, Wash.

Application April 22, 1946, Serial No. 128,828

Term of patent 14 years

(Cl. D31—4)

To all whom it may concern:

Be it known that Myron C. Miller, a citizen of the United States, residing at Seattle, in the county of King, Washington, has invented a new, original, and ornamental Design for a Fish Lure, of which the following is a specification, reference being had to the accompanying drawing, forming a part thereof, in which:

Fig. 1 is a perspective view of a fish lure showing my new design;

Fig. 2 is a plan view of the fish lure of Fig. 1;

Fig. 3 is a side elevation of the fish lure of Fig. 1;

Fig. 4 is a rear elevation of the fish lure of Fig. 1; and

Fig. 5 is a front view of the fish lure of Fig. 1.

I claim:

The ornamental design for a fish lure, as shown.
